UNITED STATES PATENT OFFICE.

HENRY C. BROWN, OF FORTUNA, CALIFORNIA.

GOLD-AMALGAMATOR.

1,369,388.

Specification of Letters Patent. Patented Feb. 22, 1921.

Application filed January 21, 1920. Serial No. 353,050.

To all whom it may concern:

Be it known that I, HENRY C. BROWN, a citizen of the United States, residing at Fortuna, in the county of Humboldt and 5 State of California, have invented certain new and useful Improvements in Gold-Amalgamators, of which the following is a specification.

My invention is an improved gold amalgamating machine.

The object of my invention is to provide a machine to amalgamate gold which is so fine that it will not settle on the ordinary gravity plate and to clean greasy gold and 15 brighten it so that that it will amalgamate.

Referring to the annexed drawing which forms a part of this specification:

Figure 1 is a vertical longitudinal section 20 of my invention.

Fig. 2 is a face view of one of the agitators.

The parts of my invention are designated 25 in the drawing by the same reference characters designating corresponding parts in the specification.

In the drawing 1 indicates a cleaner and 30 2 an amalgamator. The cleaner 1 includes a cylinder 3, a shaft 4 extending through the heads 5 and 6 of said cylinder, and journaled in bearings 7 and 8, agitators 9, 10, 11 and 35 12 secured on said shaft within said cylinder and a pulley 13 secured on said shaft through which power is applied to rotate said shaft and agitators. Packing 40 boxes 14 and 15 are arranged in the heads 5 and 6. Each of the agitators 9, 10, 11 and 12 is of disk formation slightly smaller in diameter than the interior of the cylinder 3 and is provided with two diametrically opposite slots 16 which extend through the periphery thereof. On the right or receiving side of each of said agitators are a pair of flanges 17, each of which extends eccentrically of the center of the agitator from a 45 point near the periphery thereof and near one side of a slot 16 to the periphery of the agitator and to the same side of the other slot 16. In the upper wall at the receiving end of the cylinder 3 is an inlet 20 with 50 which the lower end of a hopper 21 communicates, the hopper being secured to the cylinder. In the lower wall of said cylinder at the discharge end thereof is an outlet 22 which communicates with a discharge tube

23 secured at its receiving end to said cylinder.

The amalgamator 2 is conical shaped including a head 24 and a conical shell 25, said head being formed with an in-turned peripheral flange 26 which fits within the 60 smaller end of said shell and is riveted thereto. The head 24 is provided with a central opening 27 and a tubular journal 28 is secured at one end to the outside of said head in communication with said opening and 65 coaxially with the head and shell 25. The journal 28 is journaled horizontally in bearings 29 and 30 in standards 31 and 32. The tube 23 curves downwardly from the outlet 23 into a horizontal direction into the journal 70 28. A pulley 33 is secured on the shaft 4 between the bearing 8 and the cylinder head 6 and a pulley 34 of greater diameter than pulley 33 is secured on the amalgamator journal 28, over which pulleys extends a belt 75 35 whereby the amalgamator is rotated from the shaft 4. A distribution plate 36 is located in the amalgamator a short distance in from the head 24, which plate is of concave-convex formation and has an outer annular flange 37, the concaved side of said plate facing the head 24 and the inlet 27. Bolts 38 extend through the head 24 and through the flange 37 and nuts 39 screw on the inner ends of said bolts against said 80 flange whereby the distribution plate is maintained in position. The amalgamator shell 25 is lined with a copper lining 40. A sluice box 50 is located below the outer end of the amalgamator 2.

The operation of my invention is as follows:

A small amount of mercury is thrown into the amalgamator which spreads out in a thin film over the inner surface of the copper 95 lining 40. An emulsion of water and sand containing gold is fed through the hopper 21 into the cleaner 1, in which the agitators 9 to 12 inclusive set up currents and counter currents and cause the sand and water to 100 cut and wash any gold contained in the sand. The cleaner permits the use of a large quantity of water which is so essential in handling greasy gold. The emulsion passes from the cleaner through the pipe 33 into 105 the amalgamator delivering the emulsion between the head 24 and the distributor plate 36. The amalgamator revolves just

fast enough to force the emulsion, by centrifugal force, out through the narrow slot between the outer edge of the head flange 26 and the distributer plate flange 37 into the main chamber of the amalgamator. The distributer plate 36 gives the emulsion a rotary motion and distributes the emulsion evenly around in a circle through the slot between the distributer flange and the amalgamator head flange over the surface of the amalgamator chamber, which has a cleaning effect on the gold and eliminates the wear on the amalgamator. The amalgamator being funnel shaped carries the material along and discharges it into the sluice box 50 where the gold is collected. The amalgamator holds mercury and amalgam just as well as gravity plates, but once the gold catches on

the lining 40 it is completely amalgamated which is not the case in any other method used.

Having described my invention, I claim:

In an amalgamating machine, a cylinder, a shaft extending axially through said cylinder, disk agitators on said shaft provided with diametrically opposite slots extending through their periphery, eccentric arcuate flanges on said agitators extending from a point within the periphery thereof near one side of one slot to the periphery thereof and to the same side of the other slot, said cylinder provided with an inlet and an outlet, an amalgamator, and a pipe leading from said outlet to said amalgamator.

In testimony whereof I affix my signature.

HENRY C. BROWN.
